(57) **CLAIM**

The ornamental design for a tank for an agricultural machine, as shown and described.

DESCRIPTION

FIG. 1 is a front perspective view of a tank for an agricultural machine;

FIG. 2 is a rear perspective view of the tank for an agricultural machine as in FIG. 1;

FIG. 3 is a left side elevational view of the tank for an agricultural machine as in FIG. 1;

FIG. 4 is a right side elevational view of the tank for an agricultural machine as in FIG. 1;

FIG. 5 is a front elevational view of the tank for an agricultural machine as in FIG. 1;

FIG. 6 is a rear elevational view of the tank for an agricultural machine as in FIG. 1;

FIG. 7 is a top plan view of the tank for an agricultural machine as in FIG. 1; and,

FIG. 8 is a bottom plan view of the tank for an agricultural machine as in FIG. 1.

1 Claim, 8 Drawing Sheets
